WINDOW CLEANING APPARATUS

Filed July 24, 1931

UNITED STATES PATENT OFFICE

FREDERICK SHEINMAN, OF NEW YORK, N. Y.

WINDOW CLEANING APPARATUS

Application filed July 24, 1931. Serial No. 552,870.

This invention relates to apparatus for cleaning windows, and is especially adaptable for use in cleaning the outer surfaces of the window panes; and the object of the invention is to provide an apparatus of the class specified, involving a light weight, yoke-shaped frame, one arm of which constitutes a handle member and the other arm including telescoping parts having means on the outer or upper part for detachably supporting a cleaning element in connection therewith; a further object being to provide a flexible shaft for placing an electric motor in operative connection with the cleaning element for rotating the same, said flexible shaft passing upwardly through said telescoping members, and means for coupling said shaft with a gearing disposed in a casing supported on the outer or upper telescoping member; a further object being to provide means adjacent the handle member for retaining the telescoping members in different positions of adjustment; a further object being to provide means for retaining the telescoping members in fully extended position; a still further object being to provide an electric switch on the handle member of said frame for controlling the circuit to said electric motor to control the operation of said cleaning element; and with these and other objects in view, the invention consists in an apparatus of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a sectional view through a window frame, illustrating the method of using my improved cleaning apparatus; and,

Fig. 2 is an enlarged view of the frame of the device which I employ, with part of the construction broken away and in section.

For the purpose of illustrating the use of my invention, I have indicated at 5 in Fig. 1 of the drawing the frame of a window; 6 the

window opening; 7 the upper sash; and 8 the lower sash. Each sash has the usual window panels 7a and 8a. My improved cleaning apparatus comprises in the construction shown a yoke-shaped frame 9, preferably composed of light weight material of any kind or class, said frame consisting of a tubular crosshead 10 from the ends of which extend tubular arms 11 and 12. The arm 11 is shorter than the arm 12 and forms a handle member for the device having a knob 13 at its upper end.

The arm 12 is preferably rectangular in cross sectional form in order to key supplemental telescoping arms 14 and 15 thereto and to each other to prevent rotation. The supplemental arms 14 and 15 are in the form of rectangular tubes, the tube 14 being smaller than the tube 12 and the tube 15 smaller than the tube 14. The lower end of the tube 14 is apertured in one side wall as seen at 16 to receive a spring pawl or catch 17 for limiting the outward movement of the tube 14 with respect to the tube 12 and also to retain said parts in fully extended position. The lower end of the tube 15 is provided with an aperture 18, in connection with which a pawl or spring catch 19 operates for a similar purpose.

Secured to the upper or free end of the tube 15 is a casing 20, the attachment being made by a bracket 20a. Supported in the casing 20 are two beveled gears 21 and 22, the gear 21 having a shaft 23 adapted to be coupled with a flexible shaft 24 by the usual tongue and groove connection as indicated at 25. The flexible shaft 24 passes through a flexible tube 24a, and said shaft extends to and is coupled with the shaft 26 of an electric motor 27 by the usual coupling 28. The flexible tubing 24a with the shaft 24 therein is movable with the tube 15. In other words, as the tube 15 moves upwardly and downwardly, the shaft 24 including the tubing 24a moves through the tubes 12 and 14 and outwardly through an opening 29 formed in the corner portion of the frame joining the crosshead 10 with the arm or tubing 12.

Arranged in the crosshead 10 is a spring actuated clamp 30 adapted to engage the flexible tubing 24a to retain said tubing.

against movement with respect to the tube or arm 12, thus supporting and maintaining the tubes 12, 14 and 15 in different positions of adjustment. A finger piece or trigger 31 projects upwardly through the crosshead 10 to permit the withdrawal or release of the clamp 30 against the tension of its spring 32 in the adjustment of said telescoping tubes.

Arranged in the top of the casing 20 is 10 a horizontal shaft 33 on which the gear 22 is mounted. The shaft 33 projects outwardly through opposite sides of the casing and the outer ends thereof are threaded as seen at 33a and 33b to receive a nut or chuck 34

15 having an extending shaft portion 35 including a disk or head 36 upon which a cleaning element 37 is adapted to be secured by an annular clamp band 38 similar in form to conventional hose clamps.

20 The cleaning element 37 may be in the form of a cloth, chamois, brush or other article, depending upon the particular use of the invention. While a single cleaning element is shown supported on one end of the shaft, 25 it will be understood that the other end 33a of said shaft may have another element attached thereto.

To bring the other cleaning element into the 30 position of the element 37 shown in Figs. 1 and 2, I provide the coupling bracket 20a with a screw or pin 38 which may be placed in either one of two apertures 39 and 40 disposed on opposite sides of the casing, the pin 38 being in the aperture 39 in the construction shown, and when placed in the aperture 40, the casing will have been turned into position to arrange the end 33a of the shaft in the position assumed by the end 33b as shown in the drawing.

40 The casing 22 includes a bearing and coupling block 41 secured thereto by a set screw 42, and this bearing block projects below the casing and is angular in form to seat in the upper end of the tube 15, which acts as 45 a key for keying the tube and casing in alignment. It will therefore be understood, that in reversing the position of the casing, this bearing will be withdrawn from the tube 15 as will be apparent. It will be understood at 50 this time, that other means may be provided within the scope of my invention for accomplishing the interchanging of the position of the casing 20 and especially the shaft 33 therein.

55 Supported in connection with the arm or handle member 11 adjacent the knob 13 is an electric switch 43, and the circuit wires from a source of supply as indicated at 44 pass through the corner or elbow 45 and upwardly through the tubular handle member to said switch. Other wires extending from the tubular handle member are directed to the electric motor 27 as clearly illustrated in Fig. 1 of the drawing.

60 65 One of the distinctive features of my invention resides in the fact that the frame consisting of the crosshead 10 and arms 11 and 12, including the supplemental arms 14 and 15 and the casing 20 and its parts are all composed of comparatively light material, and are independent of the heavy electric motor which is supported upon the floor or other surface. By reason of this fact, the frame may be conveniently manipulated upwardly and downwardly and transversely of the window opening to move any desired cleaning element such as the element 37 over the outer surfaces of the transparent panels or window panes 7a and 8a of the sashes 7 and 8.

In the operation of the device, it will be understood that from time to time the telescoping tubes 12-14-15 will be extended and contracted in order to bring the cleaning element in position to reach both the upper and lower portions of both upper and lower sashes, or the window panels of such sashes, bearing in mind that sufficient room must be provided to permit the clearance of the crosshead 10 of the frame beneath the respective sashes.

With an apparatus made according to my invention, the outer surfaces of windows may be cleaned in an absolutely safe manner without endangering the life of the person performing the operation; and by virtue of the manner of actuating the cleaning elements herein disclosed at a relatively high speed and in the use of different types of cleaning elements, windows may be cleaned and polished in a very effective, quick and practical manner.

I am aware of the fact that machines have been devised which are supported in connection with the window frame for accomplishing the result for which my invention is designed and that other apparatus have been devised including electric motors or other drives mounted in connection with and supported by the frame which is movable relatively to the window panels, but such types of machines and apparatus become too expensive and complicated in handling and setting up, or too tiresome in the handling to render the same practical. In this respect, the distinctive features in my invention reside in the lightness and simplicity of my device, as well as the fact that the same is portable and can be conveniently moved from place to place and adjusted into its several positions of adjustment.

It will be understood that while I have shown certain details of construction for carrying my invention into effect, that I am not necessarily limited to these details, and various changes in and modifications of the construction herein shown and described may be made within the scope of the appended claim without departing from the spirit of my invention or sacrificing its advantages.

Having fully described my invention, what

I claim as new and desire to secure by Letters Patent, is:—

In an apparatus of the class described, a frame consisting of tubular frame members, 5 one constituting a crosshead, an arm extending angularly up from one end of the crosshead, said arm being composed of tubular telescoping parts, the upper part carrying a mechanism driven by a flexible shaft, said flexible shaft and a housing therefor extending through and projecting from the telescoping parts and from said frame, and a clamp 10 fixed to the crosshead to clamp the housing of said shaft to support the same and said telescoping parts in different positions of adjustment.

In testimony that I claim the foregoing as my invention I have signed my name this 21st day of July 1931.

20 FREDERICK SHEINMAN.
